CLAIM

The ornamental design for a diaper bag, as shown and described.

DESCRIPTION

FIG. 1 is a perspective view of a diaper bag showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is an exploded perspective view thereof having front and top portions of the diaper bag removed for showing interior features of the diaper bag and having a diaper changing pad for ease of illustration thereof; and,

FIG. 9 is a perspective view thereof having rear and top portions of the diaper bag removed for showing interior features of the diaper bag for use of illustration thereof.

The cross-line hatching is understood to repeat uniformly across the body of the diaper bag.
